UNITED STATES PATENT OFFICE.

SAMUEL D. STROHM, OF PHILADELPHIA, PENNSYLVANIA.

RAILWAY SIGNALING.

No. 811,105.

Specification of Letters Patent.

Patented Jan. 30, 1906.

Application filed August 29, 1891. Serial No. 404,146.

To all whom it may concern:

Be it known that I, SAMUEL D. STROHM, a citizen of the United States, residing at Philadelphia, in the county of Philadelphia and 5 State of Pennsylvania, have invented certain new and useful Improvements in Railway Signaling; and I do hereby declare the following to be a full, clear, and exact description of the invention, such as will enable others 10 skilled in the art to which it appertains to make and use the same.

My invention has relation generally to rail-ways having their lines of way and engines or trains equipped with electromagnetic appur-15 tenances for preventing collisions of trains and for avoiding danger from open draw-bridges or switches by automatically stop-20 ping the engine or train before it enters upon a block or section of the line of way whereon 25 the collisions may occur or wherein the open drawbridges or switches are included or located, and particularly to that form of the same wherein the electromagnetic appur-30 tenances at the stations, as well as those on the engine, are so constructed and arranged for action that the appurtenances at the stations are actuated or stepped to show or provide 35 "danger" by each train or engine passing a station and are not restored or re-established 40 to "safety" until all the trains or engines pass off of a block or section controlled by said appurtenances, as fully shown, described, and claimed in a type of the same in United States Letters Patent, dated May 25, 1886, 45 No. 342,499.

My invention has for its object to provide 50 for controlling the engines or trains in back-ing, as well as advancing, in such described system; for a system of station appurte-nances in which line or local batteries or gen-55 erators and varying-resistance magnets there-in are dispensed with, thereby admitting of the application of my invention to any suit-able or desired system of electric circuits for the stations; for a construction of ground-cir-60 cuits for the stations and for the engine of a simple and economical and durable construc-tion; for a system of semaphore-signals at 65 each station in addition to the train or engine controlling appurtenances, which signals are 70 actuated simultaneously with said appurte-nances and are set to "danger" or to "safety," as is usual on railways to permit the engineer to have visual signals, as usual, in addition to 75 the automatic stopping of the train at sta-tions; for shifting the contact-brushes on the

engine or motor-car and the power or sup-80 ply controlling devices therefor by the lever mechanism used for reversing the direction of travel of the engine or car; for a construction 60 of solenoid appurtenance in the engine or train circuit controlling the power or supply for the engine or motive car, whereby a longer range of motion is obtained for magnetic de-85 vices to actuate the cut-off for said power or supply; for separate electromagnetic devices on the engine or motive car for actuating va-90 rious devices—as, for instance, the power-supply cut-offs, the whistle or alarm, signals, air-brake devices, steam-jet or other fluid-sup-70 ply, and similar or other mechanism—at the time the train is automatically stopped, and for variously constructed and arranged line contact-plates and circuit connections for the station appurtenances for admitting of the 75 controlling of the trains or engines and the operation of the semaphore - signals at the stations.

My invention accordingly consists of the combinations, constructions, and arrange-80 ments of parts, as hereinafter more particu-larly described in the specification and pointed out in the claims.

Reference is had to the accompanying 85 drawings, wherein—

Figure 1 is a diagrammatic view of a form of station electromagnetic appurtenances, contact-plates, and engine or motor-car, elec-tromagnet devices, circuit connections there-90 for, and motive - power - controlling devices 95 embodying my invention, the engine or car being represented as approaching and about to make first contact with the plates at the station. Fig. 2 is a like view showing such first contact made. Fig. 3 is a view similar 95 to Figs. 1 and 2, representing the second con-tact of engine - brush at stations. Figs. 3^a and 4^a are respectively a sectional elevation, and an end view, enlarged, of circuit or ground breaking devices, partly shown in 100 Figs. 1, 2, and 3, for the magnetic appurte-nances at the stations. Figs. 4 and 5 are sec-tional elevations of the step-by-step mech-anism for actuating the circuit or ground 105 breaking devices reversely or in opposite di-rections at the stations, drawn to an enlarged scale. Fig. 6 is a perspective view of a de-vice for regulating the extent of movement of the solenoid-cores which operate the ground-breaking devices. Fig. 7 is a sectional eleva-tion of a form of switch-lever and contacts 110 for engine-circuit magnetic appliances shown

in Figs. 1, 2, and 3. Fig. 8 is a diagrammatic view showing part of line and station appurtenances with contact-plates arranged to interlock the station appurtenances—that is to say, that part of the contact-plates of a station are in circuit with the magnetic appurtenances of a distant station ahead of such plates, and the other part of said plates are in circuit-connection with the magnetic devices at a distant station to the rear of said plates—and also indicating a system of semaphore-signals for use in conjunction with said station appurtenances. Fig. 9 is a diagrammatic view of two crossing lines of railways, one equipped and the other unequipped with my improvements and the latter provided with local battery and ground connections under control of passing trains on the equipped and unequipped road for preventing collision of trains at the crossing. Fig. 10 is a diagrammatic view of a modified form of station magnetic appurtenances, contact-plates, semaphores, magnetic devices for controlling the raising and lowering of the same, and circuit connections, the same being capable of being controlled by a single contact-brush on the engine and without switching of circuit connections at the stations or in the passing train or engine, such figure also showing means for using the movements of the semaphore to switch the circuit connections between the station contact-plates and its magnetic appurtenances and also indicating the semaphore set for "safety." Fig. 11 is a like view of the semaphore and actuating mechanism, showing the former set to danger position. Fig. 12 is a view similar to Fig. 10, showing a modification of circuit or ground breaking devices for the step-by-step mechanism of the magnetic appurtenances. Fig. 13 is a longitudinal sectional view of the same. Fig. 14 is a cross-section of the circuit-breaker. Fig. 15 is a view similar to Fig. 12, showing still another modification of station appurtenances; and Fig. 16 is a plan view of a modification, showing means for changing the circuits through the brushes.

The circuit 1 1 includes an electric battery or generator a^3 , an electromagnet B , having an armature-lever b in engagement with the cut-off or throttle valve for the steam or other motive-power supply for the engine or car, with the whistle or alarm, or with the air-brake mechanism or visual signal, as fully set forth in my Letters Patent of the United States No. 662,833, dated November 27, 1900.

C , C' , and C^2 represent the station electromagnets, preferably of the form of solenoids having sliding cores. These solenoids may each have separate cores, or where any two of such cores perform the same function one core may be common to two solenoids, and in the drawings the core c is shown as being common to the solenoids C C' , and the solenoid C^2 has its own core c' . The cores c c' are

mounted in suitable frames or bearings c^2 and have retracting springs c^3 and adjustable governor-bars c^4 abutting against stops c^5 on the frames c^2 to limit the range of motion of the cores when electrically moved. The 70 governor-bars c^4 may be made adjustable by means of a slot c^6 therein and adjusting-screw c^7 on an arm c^8 on the cores, as shown more plainly in Fig. 6, or said bars may be in the form of screws in stops c^5 for the core-arms c^8 75 to abut against, as shown in dotted lines x , Fig. 2. In the preferred form of my invention the solenoids C C' C^2 are located on opposite sides of a shaft which operates the circuit-breaker D . The latter consists, as 80 shown in said Figs. 1, 2, 3, of a non-conductor disk d , having a contact point or bar d' in circuit with a frame or bracket d^2 , in which said fixed disk d is supported, and an insulated contact-finger d^3 on a shaft d^4 , having 85 ratchet-wheels d^5 d^6 , the teeth of one of said wheels being pointed or directed the reverse of those of the other. The ratchet-wheel d^6 is engaged by a spring or other equivalent pawl d^7 on one end of core c' for solenoid C^2 , 90 and the ratchet-wheel d^6 is engaged by a like pawl d^8 on one end of the core c for magnets C C' . As said wheels d^5 d^6 are fixed to shaft d^4 and have oppositely-pointed teeth, the reverse spring-actuated movements of the 95 cores c c' rotate shaft d^4 and contact-finger d^3 in opposite directions for purposes hereinafter described. To permit of such reverse rotation of the shaft d^4 , the pawls d^7 d^8 are each shown, as in Figs. 4 and 5, engaging with a 100 separate lifting-finger d^9 on a pintle d^{10} , having a crank connection d^{11} engaging a solenoid-core, so that as one of the cores c or c' moves in one direction it actuates a pintle d^{10} to oscillate its finger d^9 to throw or raise the 105 pawl on the other core out of engagement with its ratchet-wheel.

The contact-finger d^3 is in circuit with a brush d^{12} , and from station contact-plate G runs a wire or partial circuit 2 2 to ground n , 110 which circuit includes solenoid C , brush d^{12} , finger d^3 of circuit-breaker D , plate d' , and bracket d^2 when said finger d^3 and plate or point d' are in contact. When not in contact, said ground n or circuit 2 2 is broken. From station contact-plate G' leads a wire or partial circuit 3 3 to ground n , which includes solenoid C' , which circuit is always closed to ground n or never broken. From station contact-plate G^2 leads a wire or partial circuit 4 4 to ground n , which partial circuit is 120 always complete or not disrupted. The corresponding contact-plates G^3 G^4 G^5 , oppositely located relatively to the contact-plates G , G' , and G^2 , (see more plainly Fig. 8,) have 125 corresponding circuit connections 2 2, 3 3, and 4 4, respectively, which latter are split or divided circuits from the solenoids at the stations. The circuits from the plates G G' and G^3 G^4 of a station may lead directly to

the magnetic appurtenances for the stations whereat the plates are located, (see Fig. 2 for plates G G',) while those for the plates G³ and G⁵ lead, respectively, to a station to the rear 5 and ahead of the station whereat they are located. (See Fig. 2 for plate G².) I prefer, however, to lead such circuits to two stations ahead and to the rear of the station whereat the plates are located, as shown in Fig. 8, to 10 form an interlocking system of finding, breaking, and restoring the grounds n at the stations by passing trains, as set out in the afore-mentioned Letters Patent No. 662,833. When the plates G, G', and G² are located or arranged 15 out of line, as shown in Fig. 8, and the corresponding plates G³ G⁴ G⁵ similarly located, two engine-brushes a' and a² are required and an electrical switch-lever f, with contact-plates f¹, f², is included in the engine-circuit 20 11, said switch f being under the control of armature-lever b, and brush a² is in circuit with plate f² by wire 6. Upon the engine is a sliding bar F, having reaction-spring f³, (see Figs. 1, 2, and 3,) a lower end wheel or shoe 25 f⁴, and an upper latch-head f⁵ in line with a latch-head f⁶ on armature-lever b.

The brushes a' a² and bar F are suitably supported so as to be shifted from the set of line contact-plates G G' G² to the set G³ G⁴ G⁵ 30 as the engine reverses its direction of travel, or in backing and advancing any suitable manually-acting or automatic means may be used to shift said brushes and bar when necessary. In Figs. 1, 2, and 3 I have shown the 35 same supported upon an oscillating bar f⁷ and under the control of the reversing-lever f⁸ for the engine or motor-car, so that when the engine or car is reversed the brushes a' a² and bar F are shifted. Fig. 16 illustrates means 40 for shifting the contacts through which the current is led to the brushes while the brushes remain stationary. A suitably-supported sliding transverse bar F⁹, having arms f¹⁰, between which the forward end of lever f⁷ extends, and having two contact-fingers f¹¹, is 45 in circuit with the generator a³ and line 1. These fingers are adapted to conduct the current through the brushes, the latter being attached to insulated blocks a³ a⁴, from one to 50 another of which the fingers are shifted, according to the direction in which the train or engine is moving. With reference to Figs. 1, 2, and 3 it is to be understood that there are two sets of brushes used, one on each side of 55 the locomotive. These brushes are shifted by the bar f⁷, which, as shown in Fig. 16, is bent laterally back of its pivotal point and forked to receive the lower end of the lever f⁸. The brushes are attached to a sliding bar f⁹, 60 with which the forward end of lever f⁷ is connected, the arrangement being similar to that shown on Fig. 16, supposing the brushes to be attached to the bar f⁸ instead of being attached to separate supports. The plates G 65 G³ are provided with inclines or elevations

for the shoe or wheel f⁴ of rod F to move up and down or to cause said rod to ascend and descend or reciprocate at the time the brush a' is moving in contact with said plates, they serving both as contact-plates for the engine-brush and as elevations or inclines for moving the rods F

A train moving in the direction of arrow 1, Fig. 1, as it approaches a station at which the contact-finger d³ and plate d' of the circuit-breaker D is closed, set, or locked for "safety" 70 to complete the partial circuit 2 2 to ground n, as shown in Figs. 1 and 3, has its brush a' first contacting with plate G, and the engine partial circuit 1 1 by way of switch-lever f, contact f', and magnets B is closed through the station partial circuit 2 2, whereupon the armature-lever b of engine-magnets B is attracted, and its latch-head f⁶ moves out of the way of the ascending latch-head f⁵ on the 75 bar F, so that when the latter descends it does not engage the armature latch-head f⁶ and armature b is not drawn down to actuate lever b' or switch-lever f. Hence the engine travels on or is not stopped. At the same 80 time that armature-lever b is attracted the solenoid-core c is moved to cause its pawl d⁸ to get into position for engagement with ratchet-wheel d⁶ and pawl d⁷ of core c' to disengage itself from ratchet-wheel d⁵, so that 85 as soon as brush a' leaves plate G and the solenoid becomes inactive its core c and pawl d⁸ are retracted by spring c³ to move shaft d⁴ and finger d³ one step in a direction away from contact-plate d' to break the partial circuit 2 90 2 or its ground n, (see Figs. 2 and 3,) so that said finger d³ can only be moved one step at a time by a passing train whenever ground through circuit 2 2 is obtained, as the engine-brush a² then contacting with the plate G finds 95 no ground by way of circuit 1 1 on the engine, for the reason that such brush is cut out of said circuit by the switch f being in its normal position or in contact with plate f'. A following train arriving at such plate G finds 100 no ground through circuit 2 2, the engine-magnets B are inactive, and its armature latch-head f⁶ remains in the path of movement of the latch-head f⁵ of bar F and is 105 engaged by the latter as it descends and is drawn down, (see Fig. 3,) and in so moving it actuates lever b to cut off the supply of motive power and apply the brakes to stop the train. It also actuates switch-lever f to cut 110 the magnets B out of the circuit 1 1 of the engine, which circuit is then by way of plate f², wire 6 to brush a², so that when it contacts with plate G' such engine-circuit (the magnets being cut out) is closed through station partial circuit 3 3. The solenoid C' therein 115 then becomes active to move its core c, as already described, in order that the reaction of its spring c³ will move such core and its pawl d⁸ to rotate shaft d⁴ and finger d³ one step 120 farther away from plate d' of the circuit- 125 130

breaker D, said finger being now two steps away from said plate. A train then in passing a station and not finding a safety ground through plate G and circuit 2 2 is not only stopped, but also further steps the circuit-breaker D, so that the latter cannot be closed or reestablished to indicate "safety" until all the trains pass off of the section controlled by the same. Such reestablishment is made by 15 either of the engine-brushes of a train or trains contacting with plate G² to close the engine partial circuit 1 1 through the partial circuit 4 4 of a distant station to the rear of the said contact-plate, which energizes the 20 solenoid C² at such station to move its core c' and the pawl d' to reversely rotate shaft d' and finger d³ one step toward the plate d' until contact between the plate and finger is made. A suitable limiting-stop g is provided 25 on disk d to prevent the finger d³ passing beyond the plate d' when the circuit-breaker is closed to safety position. The same results occur when the train backs, as its brushes a' a² and movable bar F are shifted from the 30 line of plates G G' G² to that of plates G³ G⁴ G⁵, and this occurs either upon a single or a double track railway, the latter being illustrated in Fig. 9 and the former in Fig. 8, which shows two trains approaching each 35 other, as at z z, and breaking ground and restoring the same as they pass the stations and also two trains z z' upon one section or block and the circuit-breaker at stations Nos. 8 and 9 being separated two steps instead of one, as indicated in stations Nos. 2, 3, 4, 5, and 7, the circuit-breakers at stations Nos. 1 and 6 being closed. When the engine-circuit switch f and contacts f' and f² are used, I prefer a knife form of the latter, as shown 40 in Fig. 7, for obtaining better and surer contact.

A line of way not equipped with my improvements as herein described crossing a line of way which is equipped has local circuit connections 8 8 and 9 9, including a battery g¹², closed through a magnet g³ and a ground g⁴ by wheels and axles bridging the tracks, and the armature g⁵ for magnet g³ has a ground g⁶ and circuit connections 9 by way 45 of a stop or contact g⁷ with extra contact-plates G⁷ at the stations on the equipped line of way adjoining the crossing, which grounds are made and broken to control the movements of the trains on either line of way 50 as they approach the crossing to prevent collisions, as fully set forth in the aforesaid Letters Patent No. 662,833.

The semaphores H at the stations may be of the usual or other suitable construction and 55 are arranged to be set or fall for "safety" or "clear track" and be raised for "danger ahead," as is customary. In Fig. 8 I have indicated these semaphores as having separate actuating devices h included in the station-circuits 2 2 for lowering the semaphores and

separate actuating devices h' included in station-circuits 4 4 for raising the same. These devices h h' may be electromagnet devices, wholly or partially so, and may be arranged to be actuated by a passing train 70 simultaneously with finding, breaking, and closing the grounds for the station magnetic appurtenances or in advance of operating the latter, as desired or the requirements of service demands. In Figs. 10 to 15 I have more 75 plainly illustrated said semaphores, their actuating mechanism and circuit connections therefor in conjunction with the station magnetic appurtenances and arranged so as to be set or fall when the circuit-breaker D in circuit 2 2 at the stations is closed to indicate "safety" and raised when the circuit-breaker D is open and to so remain to indicate "danger ahead" until said circuit-breaker is closed. In 80 said last-named figures I have shown the 85 semaphore-actuating devices h consisting of a magnet or solenoid included in station partial circuit 2 2 and having a core h³ with retracting-spring h⁴ and a finger or catch h⁵ at its upper end which is normally above the 90 semaphore and in engagement therewith, as shown. Solenoid h when energized draws down its core h³, and in so moving its catch or latch head h⁵ engages with and raises the 95 semaphore to danger position. The actuating device h' is shown consisting of a magnet included in station partial circuit 4 4, having an armature-lever h⁶ with latch-head h' for engaging the semaphore or a latch h' thereon to hold it in its raised position to indicate 100 "danger," said armature having a retracting-spring h⁸, which holds it in engagement with the semaphore, and its movement is limited by a stop h⁹. When magnet h' is energized, it attracts its armature h⁶ and disengages its latch-head from the semaphore, and it drops by gravity to indicate "safety." When a circuit-breaker D is included in station-circuit 2 2 to 110 permit of successive steppings of the breaker by two or more trains passing upon a block or section, the station-circuit 4 4 must be provided with a corresponding acting circuit-breaker K in order that the semaphore will not be raised to indicate "safety" until all of said two or more trains pass off of the block or section, and such circuit-breaker K must act synchronously with the breaker D. To this end and to reduce the parts of the electromagnetic devices in the stations, I have shown the magnets or solenoids C C' acting to open both 115 circuit-breakers D and K and yet maintain the ground-circuit for the magnet or solenoid C² for restoring or reestablishing circuit-breaker D and the said solenoid C² acting to restore or reestablish circuit-breaker K to close the 120 circuit 4 4 through magnet h'. The contact-plate k of circuit-breaker K is mounted upon but insulated from section D' and has a brush k' included in circuit 4 4. The contact-finger k² consists of a spring and is 125 130

mounted upon but insulated from the section D^2 of shaft d^4 and has a brush k^3 included in circuit 4 4. Below plate k^2 and normally out of contact with it is a contact-plate k^4 , mounted on and insulated from section D^2 and having a brush k^5 included in circuit 4 4. When both circuit-breakers D and K are closed, as shown in Fig. 10, the circuit 2 2 from plates G G^3 is first by way of solenoid C, thence to brush g , to shaft d^4 , thence through the latter to plate d' , to finger d^3 , and shaft-section D^2 , and from the latter through brush d^2 to solenoid h and to ground n . The circuit 3 3 is from plate G' G^4 , to solenoid C', to ground n , as before. The circuit 4 4 is from plates G ^{2} G^3 to solenoid C ^{2} , thence to brush k^3 , to plate k^2 , to finger k , to brush k' , to magnet h' , and ground n . From plate k^4 and brush k^5 leads a wire 4' to ground n . A train or engine brush a' approaching and contacting with plates G or G ^{3} closes engine-circuit 1 1 through station-circuit 2 2 and the circuit-breakers D and K being closed finds ground n through solenoids C and h or "safety," the semaphore being in its fallen or safety position. The solenoid h is energized and draws down its core h^3 , and with it the semaphore, to set it in its raised or danger position, and at the same time the solenoid C acts as hereinbefore described to cause its core c to step the plate d' away from finger d^3 of circuit-breaker D to break the circuit 2 2 or its ground n . The plate k at the same time is moved off of finger k^2 to open circuit-breaker K and cut the magnet h' out of the circuit 4 4, so that its armature h^8 , through its spring h^8 , will catch and engage the semaphore and hold it in its raised position until said magnet is cut into the circuit 4 4 and attracts its armature to release the semaphore, which is done at the moment the circuit-breakers D and K are closed or restored. When the plate k passes off of finger k^2 , as above described, the latter immediately contacts with plate k^4 , and circuit 4 4 is grounded to n by way of plates k^2 k^4 , brush k^5 , and wire 4' and is so grounded as long as the breaker K is open. Following trains arriving at plate G before the leaders have passed off of the block or section find no ground through plate G and are stopped, the raised semaphore also indicating to the engineer "danger ahead." Contact of the engine-brush a^2 with plates G' G^4 finds ground through solenoid C' for stepping the circuit-breakers still farther apart, as above described. As the trains pass off of the section or block the contact of the engine-brushes with plates G ^{2} G^3 closes circuit 1 1 thereof through station-circuit 4 4 by way of plates k^2 k^4 , brush k^5 , and wire 4' to cause the solenoid C ^{2} or its core to act to step shaft D or movable parts k^2 d^3 toward the corresponding parts k and d , and as the last train leaves the

block and contacts with said plates the circuit-breakers D and K are closed, restoring 65 the ground n for circuit 2 2 and the ground n for circuit 4 4 by way of magnet h' , which is energized, attracts its armature, and releases the semaphore, which falls to indicate "safety." To effectually provide for shifting the circuit 4 4 from wire 4' to magnets h' at the time of closing the circuit-breaker K and without breaking or opening such circuit, the plate k on the edge approached by the finger k^2 is beveled or inclined, as shown 75 more plainly in Fig. 14, so that the plate k^2 will contact with finger k before it leaves the plate k^4 . Instead of using separate wire connections between the plates G and G' or G ^{3} and G ^{4} and the solenoids C C' they may be 80 connected by a single wire, having an electric switch 21, shifted by the movements of the semaphore from contacts 22 and 23 in circuit with said plates, as indicated in Fig. 10, such switch 21 being used to break the 85 grounds for solenoids C C' as required to effect the results above described when the single wire 20 is employed. In Figs. 12, 13, and 15 the shaft d^4 is shown in one piece and separate tubular sleeves or shafts D' D^2 , mounted 90 thereon, upon which are located, but duly insulated, the respective parts of the circuit-breakers D and K, Fig. 13 showing the latter closed and Figs. 12 and 15 showing them opened. 95

I do not herein claim the construction and arrangement of semaphore-actuating mechanism controlled by passing trains in the manner described independently of automatically controlling the movements of the engines 100 or trains, as the same forms the subject-matter of another concurrent pending application, Serial No. 404,149.

It will be noted from the foregoing that each station, as shown, has three separate 105 partial circuits, each of which is an open circuit in itself, two of which are always grounded, and the other is normally grounded and includes a circuit-breaker and magnetic devices for actuating the breaker to break its 110 ground by a current from a passing train; one of the other circuits including magnetic devices for restoring such ground, thereby dispensing with line-wires or closed battery-circuits for the station devices and with different resistance magnetic devices for the stations; that the semaphore is set to "danger" when the ground of the partial circuit adapted to be broken is broken and remains in danger position until such ground is restored; that for controlling the movement of the train in backing as well as going forward two sets of contact-plates oppositely arranged are provided, which are included in said partial circuits by branch wires or conductors, so that but a single station device or 115 120 125

box is required for each station for each line of tracks of a railway for controlling the movements of trains in either their forward or backward movements irrespective of the direction of their initial forward movement.

What I claim is—

1. A railway having a plurality of stations, a circuit making and breaking device at each station controlling a safety appliance, two separate sets of oppositely-located contact-plates at each station, a normally closed partial circuit extending from one of the contact-plates of one set through the circuit-breaker of a distant station in advance of the same and adapted when operated to break the said partial circuit, a partial circuit extending from another contact-plate of the same set through the same distant circuit-breaker and adapted when energized to further break the first partial circuit, a partial circuit extending from the third contact-plate of the same set to a circuit-breaker behind the same so as to reestablish the same if broken, a normally closed partial circuit extending from one of the contact-plates of the other set to a circuit-breaker of a distant station behind the same and adapted when operated to break said partial circuit, a partial circuit extending from another contact-plate of the same set to the same distant circuit-breaker and adapted when energized to further break the first-mentioned partial circuit, a partial circuit extending from the third contact-plate of the same set to a circuit-breaker in advance of the same and adapted to restore the same if broken, a generator with connections, and circuit-making devices on a train making contact with either of said sets of contact-plates according to the direction of movement of the train, and thereby complete the corresponding partial station-circuits, substantially as set forth.
2. In a railway having a plurality of stations, the combination of a step-by-step circuit-breaking device at each station, two magnets or solenoids for operating the same, two contact-plates at each station, a partial circuit connected with one of said contact-plates and extending through one of said magnets or solenoids and adapted to be broken by said circuit-breaker, a safety device under the control of said circuit, a second partial circuit connected with the other of said contact-plates and extending through the other magnet or solenoid, a generator with connections and contact-making devices on a train making contact with said contact-plates to complete said partial circuits, and a switch controlled by the safety device for supplying current to the second partial circuit only when the safety device is operated, substantially as set forth.
3. In a railway having a plurality of sta-

tions, the combination of a step-by-step circuit-breaking device at each station, two magnets or solenoids for operating the same, two contact-plates at each station, a partial circuit connected with one of said contact-plates and extending through one of said magnets or solenoids and adapted to be broken by said circuit-breaker, a magnet B on the train and adapted to be looped in said partial circuit, a latch b, the position of which is controlled by said magnet, a hooked arm F adapted to be moved upward at each station and engaging with the latch b when the magnet B is deenergized, a safety device controlled by the latch b, a second partial circuit connected with the other of the contact-plates and extending through the other magnet or solenoid at the circuit-breaker, a generator with connections and contact-making devices on a train making contact with said plates to complete said partial circuits, and a switch connected to the latch b for supplying current to the second partial circuit only when said latch is operated, substantially as set forth.

4. In a railway having a plurality of stations, the combination of a step-by-step circuit-breaking device at each station, two magnets or solenoids for operating the same, two contact-plates at each station, a partial circuit connected with one of said contact-plates and extending through one of said magnets or solenoids and adapted to be broken by said circuit-breaker, a magnet B on the train and adapted to be looped in said partial circuit, a latch b, the position of which is controlled by said magnet, a hooked arm F adapted to be moved upward at each station and engaging with the latch b when the magnet B is deenergized, connections between said latch and the throttle-valve of an engine, a second partial circuit connected with the other contact-plate and extending through the other magnet or solenoid at the circuit-breaker, a generator with connections and contact-making devices on a train making contact with said plates to complete said partial circuits, and a switch connected to the latch b for supplying current to the second partial circuit only when said latch is operated, substantially as set forth.

5. In a railway having a plurality of stations, the combination of a circuit making and breaking device at each station having two magnets or solenoids for effecting the breaks, and a single magnet or solenoid for effecting the reverse movements of said device, and three contact-plates at each station with each of which a partial circuit connects, one of said partial circuits controlling the safety device and extending through one of the breaking magnets or solenoids which when operated will break said partial circuit,

the second partial circuit extending through the other breaking magnet or solenoid so that a second train entering the block will further break the first-mentioned circuit, and the 5 third partial circuit extending through the resetting magnet or solenoid of a distant station, a generator with connections and circuit-making devices on a train engaging said contact-plates to complete the corresponding 10 partial station-circuits, substantially as set forth.

6. In a railway having a plurality of stations, the combination with a circuit making and breaking device at each station having 15 two magnets or solenoids for effecting the breaks, and a single magnet or solenoid for effecting the reverse movements of said device, three contact-plates at each station, with each of which a partial circuit connects, 20 one of said partial circuits controlling the safety device and extending through one of the breaking magnets or solenoids, which when operated will break said partial circuit, the second partial circuit extending through 25 the other breaking magnet or solenoid, so that a second train entering a block will further break the first-mentioned circuit, and the third partial circuit extending through the resetting magnet or solenoid of a distant 30 station, and a generator with connections, of two contact-making devices on a train, one of which engages the first contact-plate to break the said first partial circuit whereby the safety device is operated and the other of which engages the second contact-plate, and a switch operated in connection with the safety device for supplying current to the second contact-plate only when the first circuit is broken, substantially as described.

40 7. In a railway having a plurality of stations, the combination with a circuit-making device at each station having two magnets or solenoids for effecting the breaks, and a single magnet or solenoid effecting the reverse movements of said device, three contact-plates at each station with each of which a partial circuit connects, one of said partial circuits controlling the safety device and extending through one of the breaking magnets or 45 solenoids, which when operated will break said partial circuit, the second partial circuit extending through the other breaking magnet or solenoid, so that a second train entering the block will further break the first-mentioned circuit, and the third partial circuit extending through the resetting magnet or solenoid at a distant station, and a generator with connections of two contact-making devices on a train, one of which engages with 50 the first contact-plate to break said first partial circuit, and the other of which engages with the second contact-plate, of a magnet B to be looped in the first partial circuit, a latch

b, the position of which is controlled by said magnet, a hooked rod F adapted to be moved 65 upward at each station for engaging the latch b when the magnet B is deenergized, and a switch f for cutting the second partial circuit into circuit with the source of supply when said latch is moved downward for actuating 70 the safety device, substantially as described.

8. In railway signaling, the combination of a step-by-step circuit-breaker and a semaphore at each station, means for setting said semaphore, an electromagnetic latch for tripping the same, a tripping-circuit extending from a distant station to the circuit-breaker and in circuit with the magnetic tripping device of the semaphore when the parts of the circuit-breaker are in normal condition, and 80 contact devices operated by the circuit-breaker for grounding said tripping-circuit when the circuit-breaker is not in normal condition, substantially as and for the purpose set forth. 85

9. In railway signaling, the combination of a step-by-step circuit-breaker carrying two fingers K, K², which normally are in contact, a second finger K⁴ with which the finger K² makes contact when the same is separated 90 from the finger K, a semaphore at each station, means for setting the same, an electromagnetic tripping device for tripping said semaphore, a tripping-circuit extending in series with the fingers K², and K', and with 95 said tripping device, and a ground connected with said finger K⁴ whereby when the circuit-breaker is in normal condition the tripping-circuit will extend through said tripping device, while if the said circuit-breaker is not in 100 normal condition the said tripping-circuit will be grounded and will not affect the tripping device, substantially as set forth.

10. A railway having station electromagnetic devices, contact-plates and circuit connections, a semaphore, electromagnetic devices for setting the semaphore to one position, separate locking mechanism for holding said semaphore in said position, electromagnetic devices for releasing said locking devices for returning said semaphore to normal position, said electromagnetic locking and releasing devices being included in the circuits of the station-electromagnets, substantially as set forth. 115

11. In combination with station electromagnetic circuit connections for automatically stopping a railway train or engine, a semaphore, electromagnetic devices included in said circuit connections for setting the 120 semaphore to a signaling position, locking devices for holding it in said position, and electromagnetic devices included in said circuit connections for releasing said locking devices and restoring the semaphore to normal position, substantially as set forth. 125

12. A station electromagnetic appurtenance comprising a magnet having a circuit-breaker, a second electromagnet having a circuit-breaker, the former or first named magnet acting to open both circuit-breakers simultaneously, and the second-named magnet to correspondingly close the same, one of said breakers when opened automatically making

a separate ground connection for said magnet substantially as set forth.

In testimony whereof I affix my signature in presence of two witnesses.

SAMUEL D. STROHM.
